INVENTOR

UNITED STATES PATENT OFFICE

102,652

DESIGN FOR A RIBBON ROLLER RACK

Oscar Lion, New York, N. Y.

Application November 5, 1936, Serial No. 65,697

Term of patent 3½ years

To all whom it may concern:

Be it known that I, Oscar Lion, a citizen of the United States of America, residing in Manhattan, county of New York, and State of New York, have invented a new, original, and ornamental Design for a Ribbon Roller Rack, of which the following is a specification, reference being had to the accompanying drawing, forming part thereof, wherein,

I claim:

The ornamental design for a ribbon roller rack, substantially as shown.

OSCAR LION.
